(57) **CLAIM**

The ornamental design for a powder inhalator, as shown and described.

DESCRIPTION

FIG. 1 is a perspective view of a powder inhalator showing our new design with a translucent cap in a stored position; FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front elevational view of the powder inhalator of FIG. 1 with the translucent cap removed;

FIG. 9 is a perspective view of FIG. 8;

FIG. 10 is a front elevational view of FIG. 8;

FIG. 11 is a rear elevational view of FIG. 8;

FIG. 12 is a right side elevational view of FIG. 8;

FIG. 13 is a left side elevational view of FIG. 8;

FIG. 14 is a top plan view of FIG. 8;

FIG. 15 is a bottom plan view of FIG. 8; and,

FIG. 16 is a front elevational view thereof shown in compressed condition.

The broken line showing is for illustrative purposes only and forms no part of the claimed design.

UNITED STATES PATENT AND TRADEMARK OFFICE
CERTIFICATE OF CORRECTION

PATENT NO. : Des. 527,816 S
APPLICATION NO. : 29/208946
DATED : September 5, 2006
INVENTOR(S) : Toru Nishibayashi et al.

Page 1 of 1

It is certified that error appears in the above-identified patent and that said Letters Patent is hereby corrected as shown below:

Title page, item (73) "Otsuka Techno Corporation , Tokyo," should read --Otsuka
Techno Corporation, Tokushima--.

Signed and Sealed this

Twelfth Day of December, 2006

A handwritten signature in black ink, appearing to read "Jon W. Dudas", is centered within a dotted rectangular box.
